Attorney.

UNITED STATES PATENT OFFICE.

JOSEF NICKL, OF OBERNDORF-ON-THE-NECKAR, GERMANY, ASSIGNOR TO WAFFEN-FABRIK MAUSER, AKTIENGESELLSCHAFT, OF OBERNDORF-ON-THE-NECKAR, GERMANY.

RECOIL-LOADING PISTOL.

1,413,185.

Specification of Letters Patent. Patented Apr. 18, 1922.

Application filed June 16, 1921. Serial No. 478,211.

To all whom it may concern:

Be it known that I, JOSEF NICKL, a citizen of the German Republic, residing at No. 8 of Hauptstrasse, in the city of Oberndorf-on-the-Neckar, Germany, have invented 5 certain new and useful Improvements in Recoil-Loading Pistols, (for which I have filed applications in Germany Apr. 20, 1916; France Mar. 30, 1921; Belgium Mar. 31, 10 1921; Spain Mar. 30, 1921; Sweden Mar. 29, 1921; Italy Mar. 29, 1921; Poland Jan. 17, 1920; Rumania Feb. 20, 1920; Austria Apr. 16, 1917; Turkey Sept. 10, 1918; Hungary May 2, 1917; Czecho-Slovakia Dec. 22, 15 1919,) of which the following is a specification.

This invention relates to a hammer-actuated recoil-loading pistol, having a breech-slide provided with grooves and adapted to 20 slide and reciprocate on guiding ribs of the grip-stock after firing.

The object of the invention is to provide a weapon with means for preventing, in case of fracture of the breech-slide, the broken 25 off rear portion of the said breech-slide from flying out and hurting the shooting person. To this end one or both guiding ribs of the grip-stock and the corresponding groove or 30 grooves of the breech-slide are stepped, recessed or shaped, as regards their dimensions, in a manner, that in case of fracture the broken off rear-portion of the breech-slide is caught and retained within the pistol.

35 Referring to the accompanying drawings, which illustrate one embodiment of the invention, to the details of construction of which the invention is not limited, however, the less so since only one groove and rib is 40 shown to be stepped, while both grooves and ribs may be stepped, without thereby departing from the gist of the invention.

Figure 1 is a side view of the pistol with the handle broken off,

45 Figure 2 is a horizontal longitudinal section on the line 2—2 of Figure 1,

Figure 3 is a front view of the grip-stock and Figure 4 is a view of the breech-slide seen from below.

50 The grip-stock *a* has two lateral guiding ribs *b* and *c* adapted to co-act with corresponding grooves *e* and *f* in the breech-slide *d* in order to guide the latter in its reciprocal movements, as usually in pistols of this 55 type. In the shown embodiment of the in-

vention the front part of the guiding rib *b* denoted by the arrow-line *x*, Figure 1, is of less width than the rear part of the rib marked by the letter *y*, so that a step or shoulder *g* is formed serving as an abutment or stop for the breech-slide, provided to receive and co-act with the rib *b* of the grip-stock, and said slide is cut out or shaped in its front part back to the point *h* to just have a sufficient width to snugly embrace or 60 enclose the rib *b*, so that the breech-slide will be guided in its reciprocatory movements without any undue play. From said point *h* backwards the groove *e* is of increased width in conformity with the larger 65 part *y* of the guiding rib *b* so that the breech-slide upon firing does not encounter any impediment in its backward travel. This backward movement of the breech-slide is limited by the returning spring connect- 70 ed with the front end thereof as is generally known in pistols of this kind.

In case of an accidental fracture of the breech-slide at firing the broken off rear part of the slide is released from the action of 80 the returning spring and runs freely backwards, until the point *h* of the guiding groove *e* meets the step *g* of the guiding rib, whereby the run of the said broken off part is stopped and the part is prevented 85 from flying out. The step *h* is provided at a point where the cross-sectional area of the breech-slide is such as to avert fracture.

It goes without saying that as already 90 stated, the other guiding groove and the rib *c* may be stepped in a similar manner, and the result aimed at by the invention may likewise be realized by recessing or stepping the ribs and grooves in a direction rectangular to that shown in the illustrated embodiment of the invention without thereby departing from the gist of my invention. 95

What I claim to secure by the Letters Patent is:

1. In a recoil-loading pistol, the combination of a barrel, a grip-stock, a breech-slide guided thereon, a guiding rib on said grip-stock having a stepped portion, and a guiding groove in said breech-slide having a correspondingly shaped portion or step to engage 100 with the said step of the guiding rib in case of accidental fracture of the breech-slide at 105 firing.

2. In a recoil-loading pistol, the combination of a barrel, a grip-stock, a breech-slide 110

- thereon, two guiding ribs on said grip-stock having each a stepped portion, and two guiding grooves in said breech-slide having each a correspondingly shaped portion or step.
- 5 3. In a recoil-loading-pistol, the combination of a barrel, a grip-stock, a breech-slide thereon, a guiding rib on said grip-stock having a portion recessed in regard to its depth to form a step, and a guiding groove 10 in said breech-slide correspondingly shaped.
4. In a recoil-loading pistol, the combination of a barrel, a grip-stock, a breech-slide thereon, two guiding ribs on said grip-stock having each a portion recessed in regard to 15 their depth to form steps, and two guiding grooves in said breech-slide shaped correspondingly.
5. In a recoil-loading pistol, the combina-

tion of a barrel, a grip-stock, a breech-slide thereon, a guiding rib on said grip-stock having a portion recessed with regard to its depth to afford a step, and a guiding groove 20 in said breech-slide correspondingly shaped.

6. In a recoil-loading pistol, the combination of a barrel, a grip-stock, a breech-slide 25 thereon, two guiding ribs on said grip-stock having each a portion recessed in regard to their depth to form steps, and two guiding grooves in said breech-slide correspondingly shaped. 30

In testimony whereof I affix my signature in presence of two witnesses.

JOSEF NICKL.
